UNITED STATES PATENT OFFICE.

FRANK W. NORTON, OF CEDAR RAPIDS, IOWA.

PHOTOGRAPHIC-PRINTING MACHINE.

1,149,852.

Specification of Letters Patent. Patented Aug. 10, 1915.

Application filed June 11, 1914. Serial No. 844,457.

To all whom it may concern:

Be it known that I, FRANK W. NORTON, a citizen of the United States, residing at Cedar Rapids, in the county of Linn and 5 State of Iowa, have invented certain new and useful Improvements in Photographic Printing Machines; and I do hereby declare the following to be a full, clear, and exact description of the invention, such as will 10 enable others skilled in the art to which it appertains to make and use the same.

This invention relates to the art of printing photographs mechanically and by the use of artificial light, and the object of 15 the invention is to produce a machine adapted for the rapid and uniform printing of such photographs, either from single negatives, or a plurality thereof, the machine being designed to give a very quick lift of 20 the platen and ejection of the printed sheet, and comparatively long periods of opening for the insertion of a fresh sheet, and of closure for the printing of the same.

The nature of the invention is fully dis- 25 closed in the description and claims following, reference being had to the accompanying drawing, in which—

Figure 1 is a side, mid-sectional view of 30 a printing machine embodying my improvements. Fig. 2 is a plan view of the same, with parts broken away to show mechanism below, the cover or platen being removed. Fig. 3 is a similar view of a printing frame. Fig. 4 is a fragmentary, sectional view, 35 showing the electrical connections of the lamps with the cam-wheel which actuates the platen. Fig. 5 is a fragmentary, vertical section of the printing frame. Fig. 6 represents a shading sheet for a negative. Fig. 7 40 is a diagrammatic view of the electrical wiring and connections. Fig. 8 shows a removable extension of the main cam.

In the drawing 1 denotes a light-chamber, which is a box of suitable size, closed 45 on all sides except the top. In practice the box is provided with a lower extension 2, somewhat larger in area than the upper box, and provided with a bottom 3 sliding in and out between cleats 4. This compartment 50 holds the driving motor 5, which in practice may be a three-speed fan motor of a very simple and inexpensive type. The motor is of well known construction, and need not be

described. Its attachment to the side of the box is shown in Fig. 2, the speed-changing 55 lever 6 projecting through a slot in the back of the box. The driving belt 7 passes through holes in the top of this lower chamber, and transmits motion from the motor pulley 8 to a pulley 9 mounted on a 60 stud 10 projecting from an arm 11 of the main standard, to be more fully described presently. Besides its use as a receptacle for the motor, the lower chamber is em- 65 ployed as a packing-box for the main standard and the wheels and pulleys mounted thereon, these being dismounted from the assembled position shown, and packed for shipment in said box. When in use the box is mounted on an inclined base 70 12, the inclination of the box facilitating the feeding of the machine, and the discharge of printed sheets therefrom.

The light-chamber is supplied with 75 powerful electric lights 13, four of them being herein shown. In this figure it has not been deemed necessary to show the electrical wiring, which is clearly illustrated in Fig. 7. The main switch 14 is shown at the front left corner, and a group of three plug 80 connections 15 at the side near the back.

To the top of the chamber at the back side is hinged a platen 16, adapted to close down inside the chamber, at the front at least. An arm of the platen, 17, extends back some 85 distance, and is provided with a roller 18.

To the back of the main box is attached a standard having the lower arm 11 already referred to. An upstanding arm 19 carries a stud 20 for a cone pulley 21. A stud 22 90 serves as a bearing for the main cam-wheel 23. At the rear end is a bearing 24 for a short shaft 25. One end of this shaft carries a pinion 26 engaging the large spur gear 27, indicated by a few teeth and dotted 95 outline in Fig. 1, and shown in full in Fig. 2. To the other end of the shaft is attached a pulley 28. This pulley is shown belted to a pulley 29 attached to the cone 21. Nor- 100 mally, however, it belts to the pulley 30 attached to the cone 9, the belt-length being the same for engagement with these respec- 105 tive pulleys. The normal speed is therefore much greater than that indicated by the belting in Fig. 1. The object of this construction is to give a wide range of exposure,

whereby the machine is adapted to all possible conditions in the density of negatives, or otherwise, or even the enlargement of photographs in case the structure of the machine should be modified to admit of it.

The platen is preferably lifted by a spring 31 connecting with it at one end, and at the other connecting with a bracket 32. It is depressed by a cam 33 projecting from the 10 face of the wheel 23. The wheel turns in the direction indicated by the arrow. While all that portion of the cam from 34 to 35 is passing in contact with the platen roller the platen is closed. This gives a period of 15 complete closure corresponding to nearly half a revolution of the cam-wheel. As soon as the roller passes the turn 35 the platen opens up very quickly, with a comparatively long period in the open position. 20 The advantage of this construction is that while the revolution of the cam-wheel may be relatively rapid, the dwell of the platen in the closed position gives a long period of 25 constant and uniform lighting, coming on suddenly and suddenly closing, as will more clearly appear when the operation of the light is described. So also the prolonged dwell of the platen in the open position gives relatively lengthened time for the 30 removal of the printed sheet and the insertion of a new one. The effect in both respects is to give to the machine the greatest possible speed capacity, together with great precision and uniformity in printing.

35 Illumination is secured by the following mechanical and electrical construction and arrangement: Projecting from the face of the cam-wheel is a stepped sector, which is herein shown as composed of the continuous 40 section 36, a shorter one, 37, and a still shorter one, 38. The arm 11 of the standard is made hollow to receive conductor wires, and on the face of this arm opposite and coinciding with the respective steps of the 45 sector are suitably mounted the contacts *a*, *b* and *c*, as best shown in Fig. 4. Leading from these contacts are conductors *d*, *e* and *f*, respectively, and connecting respectively with the members *g*, *h* and *i* of the group 50 of plug circuit-closers 15. At the other side of the said circuit-closers the group of conductors is united to a single conductor *j*. Another portion of the same electrical leg, *k*, has a terminal *l* suitably mounted on the 55 arm 11 to make constant contact with the hub of the cam-wheel. The other leg *m*, with its branch *m'* completes the main light circuit through the switch 14. The main line conductors are supposed to lead to a 60 power station not shown.

It will now be evident that plugging *g* will close the circuit through 36, thus giving the longest possible period of lighting as the cam wheel revolves. If *h* be plugged instead, the lighting is delayed and the period

is shorter, and in the case of *i* the period is the shortest of all. In any case, the make and break is practically instantaneous, thus reducing sparking trouble to the minimum.

It will be noted that one switch closed 70 both the light and the motor circuits, the latter through *n* and *o*, so that, assuming that the operator does not switch off the lights by pulling a comparatively inaccessible plug, the switching off of the lights 75 also stops the motor, and there is thus little danger of its being injured through forgetfulness.

The machine is provided with removable frames for the negatives, and they may be 80 adapted to hold one or many. In the drawing I have shown a frame specially adapted for four negatives, though with a little modification it might be used with eight. So also it will be understood that the spacing might be adapted for two, three, one, or other number. The frame is described as 85 follows: 40 is a rectangular frame, open top and bottom, and fitting neatly, but removably, the inside of the light chamber at the 90 sides and front. It is suitably supported in the position shown in Fig. 1, as by side cleats 41. About midway of its depth is a plate of window glass 42. A little above this, separated from the lower glass by a narrow 95 strip 43 is a rectangle of plate-glass 44. In the case of a plurality of cells, as shown in Fig. 3, these plates of thick glass are separated from each other by a sheet-metal, or the like opaque partition 45, which extend 100 upwardly as high, or nearly as high, as the upper face of the negative, that is to say, to the under side of the thin sheet-metal frame 46, which serves as a keeper for the negative. The purpose of this partition is to prevent 105 the light crossing from one negative cell to another diagonally, and the object might be attained by extending the partition high enough to meet the bottom face of the negatives, the adjoining edges of which might be rendered opaque, the height being indicated by the dotted line in Fig. 5. In practice I also extend the bottom of the middle partition downwardly to a considerable distance, as shown in Fig. 1, to form a separating curtain or screen 47 between the lights on either side. This construction 110 serves to isolate the negatives, and also serves as a means whereby their density may be equalized for printing, a matter which is 115 of course of prime importance when printing is done from a number of them simultaneously. This is done by shading the thinner ones to the density of the thickest by inserting in the pockets between the bottom 120 glass and the plate glass one or more sheets of slightly opaque material, such as tissue paper 48. The thick glass serves to soften and blend the light in its passage to the 125 negative, and when so equalized any num- 130

ber within the capacity of the machine may be printed simultaneously with the greatest precision and uniformity.

In the case of the printing frame shown 5 it will be understood that the sheets are printed on the lower half at each exposure, and then turned over for printing on the other half, or half-sized sheets are used, the upper half of the frame being darkened. 10 Where, as in the case of this machine, a dozen or more exposures are made in a minute there is little or no time for the operator to remove the printed sheet, and his whole attention must be given to supplying 15 fresh sheets. Provision is therefor made whereby the printed sheets are lifted from the printing position and slide out of the machine by gravity. This device will now be described.

20 Connected with each printing frame is a lifter composed of a thin strip of metal 49 and a pair of slides 50, to which it is attached, and adapted to move up and down a limited distance in ways provided for 25 them in the frame. These are preferably connected by a cross-bar 51. In the light-chamber below the bar are slidably mounted a pair of lift-rods 52 pivoted at their lower ends to a forked lever 53 pivoted at 54. The 30 rear end of this lever passes through the back of the light chamber, and connects by a rod 55 with a short lever 56 pivoted at 57. The inner end of this lever connects by a rod 58 with another short lever 59 pivoted 35 at or near the top of the chamber. The free end of this lever is inclined, as shown, and in the downward movement of the platen is engaged by a hook 60 pivoted thereto, and held to engaging position by a spring 61. 40 The hinge of the platen and the pivot of the beveled lever are on different centers, and it is evident that when the platen reaches a certain height the parts will disengage. The first action, however, as the platen rises, 45 is to force the lifter upwardly. This carries the lower edge of the printed sheet, which rests upon it, up high enough to clear the top of the light chamber in front, when the sheet instantly slides out of the machine by 50 gravity. This takes place before the hook and the lever 59 disengage. Thereupon the lifter drops to normal position by gravity, and the operator feeds in a new sheet.

55 It is to be noted that there is no connection between the lifting mechanism attached to the light-chamber and the lifter fitted to the printing frame. This make it possible to change printing frames in a moment, by simply lifting one out and setting another in 60 its place.

It will be understood that the belt 62 connecting the cone pulleys need not necessarily be removed at any time, the large cone being simply an idler when the belting is from the 65 smaller cone to the pulley 28.

The larger moving parts are preferably made of aluminum, as by this means it has been possible to operate the machine with a high degree of efficiency with no greater power than that produced by a small fan 70 motor.

In Fig. 8 is shown another means for prolonging the period of exposure, and designed for extraordinary circumstances, in which a very long printing period is required. This consists of an attachment for the main cam, being a segmental plate 62 with screw-holes 63 coinciding with similar holes 64 in the cam, and having a cam-flange 65 fitting the flange of the cam at 75 each extremity. This, as will be evident, extends the relative period of closure of the platen, and correspondingly shortens the open period. The latter fact is not important, however, as the cam attachment 80 will only be used during the slowest operations of the machine, and when there is abundant time for the feeding operation.

Having thus described my invention, I 90 claim:

1. In a photographic printing machine having a light-chamber, electric lamps therein, and means for holding a negative in printing position, a tilting platen adapted to press the photographic sheets on said negative, and a rotating cam to actuate said platen, the cam having integrally formed electrical terminals, one in constant and the other or others in interrupted connection 95 with a light circuit.

2. In a photographic printing machine having an inclined exposure chamber and a printing frame mounted therein at a similar incline, mechanism adapted to open and close said chamber and turn on and off the lights therein, a support for the lower edge of the photographic paper, and a release therefor coöperating with the foregoing mechanism.

3. In a photographic printing machine, 110 having a light-chamber and electric lamps therein, a platen movable into and out of paper-holding position, a cam-wheel coöperating therewith, a semi-annular projection on said wheel arranged in steps, an electrical terminal in constant contact with said wheel, and a group of other terminals in the same electric circuit adapted for successive and independent contact with said projection.

4. In a photographic printing machine, 115 an inclined light-chamber having a paper-retaining ledge at its lower side, a lifter mounted beneath the paper near the lower edge when in printing position, and means adapted to elevate said lifter at the end of the printing operation.

5. In a photographic printing machine having an inclined light-chamber with a paper retaining ledge at its lower side, a re- 120

movable printing frame fitted to said chamber, a paper-lifter mounted movably in said frame, mechanism adapted to open and close said chamber and to turn on and off the lights therein, and mechanism coöperating therewith to elevate said paper-lifter at the end of the printing operation.

6. In a photographic printing machine having an inclined light-chamber with a 10 per-stop at the lower side, a pivoted platen adapted to open and close said chamber, electric lights in said chamber, and mechanism to actuate said platen and lights, a printing frame mounted in said chamber, a 15 paper-lifter connected therewith, a hook pivoted to the platen, a lever engaged by said hook during a part of the upward movement of the platen, and mechanism adapted to transfer said lifting motion to 20 said paper lifter.

7. In a photographic printing machine having a light-chamber with electric lamps therein and means for automatically opening and closing said chamber and operating said lamps, a negative-holder or printing frame fitted removably to said chamber, and divided into light-isolated cells adapted to receive separate negatives, a backing-sheet of thin glass and superimposed plates of thick glass for said cells, with interspaces adapted to receive a light arresting medium.

8. In combination with a photographic printing machine, substantially as described, a removable printing frame arranged with 25 a plurality of negative-holding cells, opaque partitions between the cells, a thick glass support for each negative and a backing sheet of thin glass at a little distance behind

it, with an interspace adapted to receive a light-arresting medium.

9. In combination with a photographic printing machine substantially as described, a removable printing frame arranged with a plurality of negative-holding cells, opaque partitions between the cells, a double glass 45 backing for said cells, with interspaces between the layers of glass, and light-arresting sheets insertible in said interspaces.

10. In a photographic printing machine having a light chamber and closing platen 50 therefor, a cam adapted to actuate said platen, a pulley and connected gearing to drive said cam, a small cone pulley and a larger cone pulley at suitable belting distance therefrom, pulleys connected with 55 each cone adapted to belt to the main pulley without change in belt length, and a motor adapted to impart motion to the small cone.

11. In a photographic printing machine having a light-chamber and a closing platen 60 therefor, a cam adapted to actuate said platen, and a removable extension of said cam adapted for attachment to the cam to prolong the closed period of the platen.

12. In a photographic printing machine, 65 the combination of a light-chamber, a closing platen and means for actuating the same, and a sub-chamber adapted to serve as a packing-box for the actuating mechanism.

In testimony whereof I affix my signature in presence of two witnesses.

FRANK W. NORTON.
